UNITED STATES PATENT OFFICE.

FLORENCE H. SWANSON, OF CHICAGO, ILLINOIS.

CONTROLLING MECHANISM FOR PHONOGRAHS AND THE LIKE.

Application filed October 14, 1921. Serial No. 507,692.

To all whom it may concern:

Be it known that I, FLORENCE H. SWANSON, a subject of the King of Sweden, residing at Chicago, in the county of Cook and State of Illinois, have invented certain new and useful Improvements in Controlling Mechanism for Phonographs and the like, of which the following is specification.

This invention relates to certain new and useful improvements in a mechanism to be used for controlling the movements of phonographs, and has particular relation to that type of such instruments known as Victrolas or Victrola phonographs, or of the disk record type, and it consists in certain peculiarities of the construction, novel arrangement and combination of the various parts thereof as will be hereinafter more fully set forth and specifically claimed.

The principal object of the invention is to provide a controlling mechanism for phonographs, graphophones, and the like, which shall be simple and inexpensive in construction, strong, durable and efficient in operation, with its parts so made and arranged that they can be readily applied to Victrolas or phonographs of the disk record type without any material alterations in the construction thereof, and in such a manner that upon completion of a piece being played thereby, the movements of the parts of the instrument will be automatically stopped.

A further object of the invention is to provide a mechanism whereby the phonograph or instrument may be manually stopped in its operation and afterwards started, if desired, at any time between the commencement and finish of the piece being played.

Still another object of the invention is to furnish a mechanism of the above mentioned general character which is applicable for use for the purposes above set forth in connection with the Victrola type or with the Brunswick type of record disks without any change or adjustment of the parts of the mechanism.

Other objects and advantages of the invention will be disclosed in the following description and explanation.

In the accompanying drawings, which serve to illustrate an embodiment of the invention—

Fig. 1 is a plan sectional view of fragments of the motor board and turn table of a phonograph taken on line 1—1 of Fig. 7 illustrating by continuous lines about the

positions the parts of the mechanism will occupy when the piece being played is almost completed, and by dotted lines about the position the tone-arm-actuated bar will occupy at the commencement of the piece being played.

Fig. 2 is a similar view of like parts showing the positions they will occupy when the piece being played is completed and the phonograph automatically stopped.

Fig. 3 is a similar view to Fig. 1 taken on the same line but showing the parts at the instant of the automatic release thereof, to permit them to assume the positions shown in Fig. 2. This view also illustrates the positions the parts will occupy when the attachment is being used in connection with a disk of the Victrola type.

Fig. 4 is a similar view to that of Fig. 3 illustrating the position of the parts when the mechanism is used in connection with a disk of the Brunswick type.

Figs. 5 and 6 are similar views to Fig. 1 taken on the same line, showing the parts in about the positions they will occupy when manually stopping and manually starting, respectively, the phonograph at a time between the commencement of playing the piece and its finish.

Fig. 7 is an enlarged sectional view taken on line 7—7 of Fig. 1 looking in the direction indicated by the arrows.

Fig. 8 is a longitudinal sectional view through a portion of the tone-arm-actuated bar.

Fig. 9 is an enlarged plan view of the inner portion of said bar, and

Fig. 10 is an enlarged perspective view of a fragment of the tripping dog and its depending projection, which dog is carried by the operating bar.

Like numerals of reference refer to corresponding parts throughout the different views of the drawings.

Referring now to the different views of the drawings, the reference numeral 12 designates a fragment of the horizontally located motor-board or plate of a phonograph or a like instrument, on the upper surface of which board and mainly within the confines of the depending annular flange 13, of the disk-like or circular turntable 14, are mounted the different elements of my controlling mechanism. The board 12 is provided centrally thereof with a vertical opening 15, for the reception of an upright spindle 16, upon

the upper end of which is mounted and supported in a horizontal position, the turn-table 14, which, as before stated, has a depending flange 13, at its periphery, and may be provided on its upper surface with a covering of felt on which the disks or records of the instrument may be positioned for use. The spindle or shaft 16, is a rotary one, and while it may be the shaft of 10 the motor of the instrument, and usually is, yet, it may be an indirectly driven rotary shaft or spindle used for imparting rotary motion to the turntable. Fixed on the shaft 16, above the board 12, is a pinion 17, which 15 meshes with a gear 18, mounted on a stub shaft 19, vertically journaled at its upper and lower ends in a bracket 20, and socket 21, respectively, mounted on the board 12, near the turntable shaft. Mounted on the 20 shaft 19, to turn therewith, is a pinion 22, which meshes with a gear 23, on a stub-shaft 24, also vertically journaled at its upper and lower ends in an arm of the bracket 20, and a socket 21, respectively, near but 25 outwardly of the first mentioned bracket and socket. The shaft 24 has fixed thereon a pinion 25, adapted to mesh with a shiftable or floating gear 26, journaled on the lower surface of and carried by a horizontally 30 disposed arm or member 27, which is pivoted at its inner end to the shaft 24, as shown. The journal shaft 28, of the gear 26, extends upwardly through the arm 27, and has 35 fixed on its upper portion a friction roller 29, which may be provided with a band 30 of felt or other suitable material to prevent slipping.

Connected to the inner portion of the arm 27, is one end of a spring 31, the other end 40 of which is secured to the bracket 20, so as to exert its tension on the said arm in the direction of the bracket. At its outer or free end the arm 27 is provided with a slot 32 which is by preference slightly enlarged 45 at its end adjacent the pivot of said arm. This slot is for the reception and operation of an upwardly extended projection 33 on the tripping and brake-shoe carrying lever which is designated as a whole by the numeral 34, and as shown in different views of 50 the drawings, extends under the flange of the turn-table and outwardly thereof. This lever is in the form of a bell-crank-lever, and is fulcrumed on the board 12 at a point 55 outwardly of the shiftable gear 26 as at 35. The shorter arm 36 of this lever is pointed to engage a pivoted arm or bar 37 near its free end. This arm or bar is pivoted as at 38 to the board 12 at one side of a straight 60 line through the shafts 16, 19 and 24 and is pressed towards said shafts by means of a spring 39 secured at one of its ends to said board. Thus it will be understood that the movement of the arm 37 which is slight, will 65 be towards and from the train of gears.

Between its outer end and the arm 36 of the lever 34, the same is provided with a laterally and upwardly extended bracket 40 which carries a brake-shoe 41 of any suitable material to impinge against the inner surface of the flange 13 of the turn-table so as to prevent rotary movement thereof. Near the fulcrum 35 of the lever 34 a releasing lever 42 has its fulcrum 43 on the board 12. This lever also extends under the flange 13 75 and outwardly thereof as is shown in different views of the drawings.

Secured at one of its ends to the inner end of the lever 42 is a spring 44, the other end of which is secured to the longer arm of the 80 lever 34 outwardly of the fulcrum 35 of the last named lever. The releasing lever 42 is prevented from pivotal movement in one direction by means of a stop-pin 45 which extends upwardly from the board 12 and is 85 adapted to engage a projection 46 on the edge of the lever 42 near its inner end. The brake-lever 34 is provided in its edge adjacent the lever 42 with a notch 47 to engage the free end of an arm 48 carried by the lever 42 and 90 extended laterally therefrom at a point between its fulcrum and the flange of the turn-table. The arm 48 has extended from the lower portion of its free end an inwardly curved releasing rod or wire 49 95 which is adapted to contact with the adjacent outer portion of the spring actuated arm 37 so as to disengage it from the pointed end of the arm 36 of the tripping and brake-shoe carrying lever. 100

Pivoted to the board 12 between the journal of the shiftable gear 26 and the bar 37 is a trigger 50 which is of a bell-crank-lever type and has a short arm 51 adapted for engagement with the pivoted arm or bar 37 105 under certain conditions. This trigger is prevented from movement in one direction by means of a stop-pin 52 extended upwardly from the board 12 in the path of the shorter arm 51 of said trigger. 110

Suitably fixed at its outer end to the upright portion of the tone-arm or reproducer carrying arm, not shown, is the operating bar which is designated as a whole by the reference numeral 53 and in the present instance is shown as comprising three bars or members 54, 55 and 56. In order for adjusting this bar for different makes of phonographs, the members 54 and 55 thereof are connected together for longitudinal adjustment, and for this purpose the inner end of the bar 54 is provided with a slot 57 for the reception of screws 58 which are extended through suitable openings in the member 55 and engage nuts 59 on the lower 115 surface of the member 54 employed for clamping the said member to the member 55 in their adjusted positions. The member 56 of the operating bar 53 is pivoted near one of its ends to the member 55 near the inner 120 125 130

end of the member 54 and as is clearly shown in Fig. 8, extends under the member 53 and beyond its inner end. The inner end of the member 56 is provided with a transverse flange 60 which has secured to its outer surface a strip of felt 61 or other suitable material to prevent slipping. At one of its sides near its flange 60 the member 56 is provided with an upwardly extended screw 62 to which one end of a slightly flexible rod 63 is secured.

As is shown in the different views of the drawing, and particularly in Figs. 8 and 9 thereof, the rod 63 is located crosswise of the upper surface of the member 56 but out of contact therewith and has its other end loosely secured by means of a screw 64 to one end of a dog 65 which is pivoted to the member 55 of the operating bar near its inner end. To prevent movement of the dog 65 in one direction, the member 55 is provided on its upper surface near the pivot of the dog with an adjustable stop block 66 which has a longitudinally disposed slot 67 for the reception of a set screw 68 seated in the member 55. By this arrangement it is manifest that the stop block 66 can be moved towards or from the dog 65 so as to regulate the movement of the dog in one direction. At its end opposite the screw or post 64 carried thereby, the dog 65 is provided with a depending projection 69 which is adapted to travel along the surface of the pivoted bar 37 adjacent the train of gears and to co-act with said bar as well as with the trigger 50 to release the bar or arm 37 from the pointed arm 36 of the tripping and brake-shoe carrying lever.

As is well known to those familiar with phonograph disk records, the type of such records used on Victrola phonographs, have their grooves arranged in convolutions spaced equi-distantly from each other, while the Brunswick type of such disks have their grooves arranged in convolutions equally distantly separated except for a few convolutions at the inner portion thereof, which are arranged in gradually wider distances apart towards the center of the disks.

From the foregoing, and by reference to the drawings, it will be readily understood and clearly seen that, assuming the parts to be in the positions shown in Fig. 1 of the drawings by continuous lines, and that the operating bar 53 carried by the tone-arm for rotation therewith has been moved by said tone-arm from the initial position of the operating bar shown by dotted lines in Fig. 1; and further assuming that the device is employed in connection with Victrola record disk, it is manifest that the friction bar or strip 60 will contact with the rotating friction roller 29, and as the latter travels faster than the shoe or strip 60 the bar 53 and its friction strip 60 will

be dragged towards the brake-shoe carrying lever 34, in which movement the projection 69 on the dog 65 will be caused by the action of the flexible rod 63 to throw the pivoted arm 37 out of engagement with the arm 36 of the brake-shoe lever 34. The position of the parts as above described are fully shown in Fig. 3 of the drawings.

After this action has taken place, the spring 44 will cause the lever 34 and its brake-shoe 41 to assume the position shown in Fig. 2 of the drawings, when it is obvious that the rotation of the turn table will be stopped by reason of the impingement of the brake-shoe 41 therewith.

When a disk of the Brunswick type is employed, after the operating arm has moved from the position shown by dotted lines in Fig. 1 to about the position shown by continuous lines in said figure, the friction strip 60 of the operating bar will contact with the friction roller 29, and as it moves with a greater degree of speed than said roller, when the stylus reaches the widened convolution of said Brunswick type of disk the dog 65 will occupy about the position shown in Fig. 4, thus causing the depending projection 69 on said dog to press the longer arm of the trigger 50 from the bar 37, thus causing the shorter arm 51 of said trigger to press the bar 37 outwardly, thus releasing it from the arm 36 of the brake-shoe lever, as is clearly shown in Fig. 4 of the drawings. From this position the parts will immediately assume the positions indicated in Fig. 2 of the drawings so as to stop the rotation of the turn-table. By connecting the elements 54 and 55 of the operating bar for adjustment longitudinally with respect to one another, it is manifest that the operating bar can be fixed at its outer end to the tone-arms of machines of different makes, especially when the distances between the tone-arms and the shaft or spindle 16 vary.

If at any time between the commencement of the piece being rendered and the finish thereof, it is desired to stop the phonograph, this can be done when the parts are in the position shown in Fig. 1, by moving the lever 42 towards the lever 34 until the rod 49 carried by the arm 48 of the lever 42 contacts with the pivoted bar 37 and disengages it from the arm 36 of the brake-shoe carrying lever.

When this release has been effected the spring 44 will retract the lever 34 until said lever strikes the free end of the arm 48 at a point outwardly from the notch 47 as shown in Fig. 2 of the drawings, when it is apparent the rotation of the turn table will be stopped by the pressure of the brake-shoe.

To manually start the phonograph, the lever 42 may be forced to the position shown in Fig. 6, when it is obvious the free end of

the arm 48 will engage the notch 47 and thus hold the brake-shoe out of contact with the flange of the turn table so as to permit rotation of the latter.

Having thus fully described my invention, what I claim as new and desire to secure by Letters Patent is—

1. In a device of the class described, the combination with the motor board of a phonograph having a vertical opening therein, of a driven rotary shaft extended through said opening, a turn-table mounted to turn with said shaft above said board and having a depending peripheral flange, a tripping and brake-shoe carrying lever fulcrumed on the motor board near the flange of the turn-table and having an arm to engage a releasing bar, said releasing bar pivoted to said board, a floating gear having connection with said lever for shifting the position thereof, a train of gears uniting the floating gear and said driven shaft, an operating arm adapted to be fixed at its outer end to the tone-arm of a phonograph to turn therewith in a horizontal plane, a friction roller carried by said floating gear, a friction member transversely disposed on the inner end of the operating bar to co-act with said friction roller, and a spring-pressed dog pivotally mounted across said operating bar and having a depending projection for co-operation with said releasing bar to disengage it from the said tripping lever.

2. In a device of the class described, the combination with the motor-board of a phonograph having a vertical opening therein, of a driven rotary shaft extended through said opening, a turn-table mounted to turn with said shaft above said board and having a depending peripheral flange, a tripping and brake-shoe carrying lever fulcrumed on the motor board near the flange of the turn-table and having an arm to engage a releasing bar, said releasing bar pivoted to said board, a spring actuated arm pivoted at one end to the motor board and loosely connected at its other end to said lever, a floating gear journaled on said arm and carrying a friction roller, a train of gears uniting the floating gear and said driven shaft, an operating arm adapted to be fixed at its outer end to the tone-arm to turn therewith in a horizontal plane, a transverse friction member on the inner end of said bar to co-act with said friction roller, and a dog pivotally mounted across said bar and having a depending projection for co-operation with said releasing bar to disengage it from the said tripping lever.

3. In a device of the class described, the combination with the motor board of a phonograph having a vertical opening therein, of a driven rotary shaft extended through

said opening, a turn-table mounted to turn the said shaft above said board and having a depending peripheral flange, a tripping and brake-shoe carrying lever fulcrumed on the motor board near the flange of the turn-table and having an arm to engage a releasing bar, said releasing bar pivoted to said board, a floating gear having spring-actuated connection with said lever for shifting the position thereof, a friction roller carried by said floating gear, a train of gears uniting the floating gear and said driven shaft, an operating arm adapted to be fixed at its outer end to the tone-arm of a phonograph to turn therewith in a horizontal plane, a friction member transversely disposed on the inner end of the operating bar to co-act with said friction roller, a spring-pressed dog pivotally mounted across said operating bar and having a depending projection for co-operation with said releasing bar to disengage it from the said tripping lever, a manually operated lever fulcrumed near the tripping lever and having an arm extended towards said tripping lever, a rod extended from the lower portion of said arm and adapted to contact with the said releasing bar, and a spring connected at one of its ends to the manually operated lever at its inner end and at its other end to the tripping lever outwardly of its fulcrum.

4. In a device of the class described, the combination with the motor board of a phonograph having a vertical opening therein, of a driven rotary shaft extended through said opening, a turn-table mounted to turn with said shaft above said board and having a depending peripheral flange, a spring actuated tripping and brake-shoe carrying lever fulcrumed on the motor board near the flange of the turn-table and having an arm to engage a releasing bar, said releasing bar pivoted to said board, a floating gear having spring actuated connection with said lever for shifting the position thereof, a friction roller carried by the floating gear, a train of gears uniting the floating gear and said driven shaft, a bell-crank-lever-shaped trigger pivoted on the board near the releasing bar and having its shorter arm adapted for engagement with said bar, an operating arm adapted to be fixed at its outer end to the tone-arm of a phonograph to turn therewith in a horizontal plane, a friction member transversely disposed on the inner end of the operating bar to co-act with said friction roller, and a spring-pressed dog pivotally mounted across said operating bar and having a depending projection for co-operation with said trigger for disengaging the releasing bar from said tripping lever.

FLORENCE H. SWANSON.
